UNITED STATES PATENT OFFICE.

FRANK J. DORSCH, OF WINONA, MINNESOTA.

WRENCH.

Application filed May 25, 1922. Serial No. 563,490.

To all whom it may concern.

Be it known that I, FRANK J. DORSCH, a citizen of the United States, residing at Winona, in the county of Winona and State 5 of Minnesota, have invented new and useful Improvements in Wrenches, of which the following is a specification.

The object of my said invention is the provision of an exceedingly strong and durable wrench of the quick adjustable type, and one that is possessed of a wide range of utility.

To the attainment of the foregoing, the invention consists in the improvement as 15 hereinafter described and definitely claimed.

In the accompanying drawings, forming part of this specification:—

Figure 1 is a side elevation of the quick adjustable wrench constructed in accordance 20 with my invention.

Figure 2 is a top plan view of the same.

Figure 3 is a transverse section taken in the plane indicated by the line 3—3 of Figure 1.

25 Figure 4 is a longitudinal section of the wrench with one jaw and its shank in elevation.

Figure 5 is a view similar to Figure 1, but showing the jaw as having smooth faces to 30 engage square and hexagonal nuts.

Figure 6 is a detail elevation showing the forward portion of a modification.

Similar numerals designate corresponding parts in Figures 1 to 4 to which reference 35 will first be made.

The jaws 1 and 2 of my novel wrench are disposed at an angle of about 60 degrees from a line extending through the longitudinal center of the wrench, and the faces or 40 opposed sides of the said jaws are preferably toothed as indicated by 3. I would have it understood, however, that it is within the purview of my invention to make the faces or opposed sides of the jaws smooth as illustrated in Figure 5, the jaws in Figure 5 being numbered 1^a and 2^a, respectively, and the said smooth faces being numbered 3^a. Manifestly when the jaws are provided with smooth faces 3^a, Figure 5, the wrench may 45 be used to advantage in turning square and hexagonal nuts and other articles of angular cross section.

The jaw 1 of the embodiment shown in Figures 1 to 4 is carried by a straight shank 50 4 on one edge of which is a series of beveled teeth 5. The jaw 2 is carried by a body 6

in which is a bore 7 for the rectilinear movement of the shank 4. It would also be noted that the body 6 is provided adjacent to the toothed edge of the shank 4 with an abutment 8 and with a projection 9, the said projection 9 carrying a portion 10 reduced in thickness and provided with a transverse aperture 11.

In addition to the elements named the 65 novel wrench comprises a lever 12. The forward end of the said lever 12 is bifurcated as indicated by 13 to straddle the body portion 10 and is pivotally connected to the said body portion 10 through the medium 70 of a pin 14. It will also be noted that the forward end of the lever 12 is square as indicated by 15, and is provided with a rounded corner 16.

From this it follows that the lever 12 when swung to a position at right 75 angles to the shank 4, will rest in said position and bear solidly against the body portion 9 so that the free end 17 of the lever may be used as a screw driver. It will also be understood that the beveled or tapered 80 nature of the said end 17 permits of a prying instrument being readily introduced between the same and the edge of the shank 4 for the starting of the movement of the free portion of the lever 20 away from the shank 85 and the body portion 8. At 18 the lever 12 is recessed to snugly receive the body portion 8 so that when the lever is in the position shown in Figure 1 and the jaws 1 and 2 are in use on a pipe or the like, the portion 90 19 of the lever 12 will thrust against the forward side of the body portion 8 and thereby take a part of the strain off the toothed roller 20 and the teeth 5 of the shank 4. The teeth 21 of the roller 20 extend entirely around the same and are beveled at their forward sides as indicated by 95 22, this provision being made in order that when the body 6 is moved forwardly on the shank 4 the teeth 21 will ride over the beveled teeth 5. The rear sides of the said teeth 21 are square faces of the teeth 5 when the wrench is in use with an object gripped between the jaws 1 and 2. It will further be apparent from Figures 1 and 4 that the 100 teeth of the roller 20 are spiral so that turning of the roller 20 about its axis will be attended by forward or rearward movement of the body 6 on the shank 4, according to the direction of rotation of the roller. The 105 roller 20 is appropriately mounted on a shaft 24, carried by the lever portion 19 and

a forward lever portion 25 spaced from the portion 19.

In the practical use of my novel wrench it will be apparent that the wrench may be quickly and easily accommodated to and used to powerfully turn a pipe or other large article of circular form in cross section.

Aside from the smooth jaw faces 3^a, the construction shown in Figure 5 may be and preferably is similar to the construction shown in Figures 1 to 4.

In the combined pipe wrench and nut wrench shown in Figure 6 the jaw 1^b on the shank 4^b is provided with an extension 30 that is equipped with a smooth face 31 arranged in parallelism with and opposed to the forward side of the body projection 9 and portion 10 so as to serve in conjunction with said projection 9 and portion 10 in forming an efficient nut wrench. Manifestly the distance between the jaw 30, on the one hand, and the body portions 9 and 10, on the other, may be varied according to the size of the nut or the like to be engaged.

In all of the embodiments of my improvement slow adjustment is effected by turning of the roller 20 about its axis while quick adjustment is attained by swinging the lever 12 on its center 14, and then using the lever as a handle with which to move the body 6 rectilinearly on the shank 4.

I have entered into a detailed description of the construction and relative arrangement of the parts embraced in the present and preferred embodiments of my invention in order to impart a full, clear and exact understanding of the said embodiments. I do

not desire, however, to be understood as confining myself to the said specific construction and relative arrangement of parts inasmuch as in the future practice of the invention various changes and modifications may be made such as fall within the scope of my invention as defined in my appended claim.

Having described my invention, what I claim and desire to secure by Letters Patent, is:—

In a wrench, the combination of a shank 50 having a fixed jaw projecting laterally from the end thereof, a shiftable jaw member 55 slideable on said shank, a toothed rack in the edge of said shank opposite said fixed jaw and formed of beveled teeth having one straight side and one inclined side, an elongated lever pivoted at one end to said shiftable jaw member and extending along the edge of said shank opposite said fixed jaw, the other end of said lever being tapered to 60 permit ready engagement of the same so as to facilitate swinging of the lever away from the shank, an adjusting worm rotatably mounted on said lever, the rear faces of the teeth on said worm being substantially parallel to a line drawn radially to the pivotal center of said worm, the front faces of said teeth being beveled, and stop means between said shiftable jaw member and said lever for limiting the outward pivotal motion of said lever to a position at right angles to the shank.

In testimony whereof, I affix my signature.

FRANK J. DORSCH.
